UNITED STATES PATENT OFFICE.

JOHN F. A. HOORT, OF NEW YORK, N. Y., ASSIGNOR TO THE EAST ROCKFORD MANTEL COMPANY, OF ROCKFORD, ILLINOIS.

DESIGN FOR A MANTEL.

SPECIFICATION forming part of Design No. 24,283, dated May 7, 1895.

Application filed April 4, 1895. Serial No. 544,499. Term of patent 3½ years.

To all whom it may concern:

Be it known that I, JOHN F. A. HOORT, a citizen of the United States, residing at New York, in the county of New York and State 5 of New York, have invented and produced a new and original Design for Mantels; and I do hereby declare the following to be a full, clear, and exact description of the same, reference being had to the accompanying drawing, forming a part thereof.

The figure of the accompanying drawing is an isometric view of the new design for mantels. Its leading feature consists in the design for a mantel comprising the mantel shelf constituting an entablature supported by composite columns each consisting of a rectangular part cut away to provide a niche for a supplementary supporting column.

Numeral 1 denotes the shelf and 2 the rect-

angular and 3 a cylindrical part of the mantel supports. The part 2 extends to the mantel shelf below which are a wide frieze 4 and an architrave 5 both situated in planes between the upper end of the parts 2 and over the columns.

The mantel shelf is at its rear surmounted by a panel frame having at its upper part a shelf 6 surmounted by a cornice 7.

What I claim is—

The design for a mantel as shown and described.

In testimony whereof I affix my signature in presence of two witnesses.

JOHN F. A. HOORT.
